UNITED STATES PATENT OFFICE.

ALOIS J. KAMPE, OF CHICAGO, ILLINOIS.

DRAFT APPARATUS FOR STOVES.

No. 913,826.

Specification of Letters Patent.

Patented March 2, 1909.

Application filed June 22, 1908. Serial No. 439,660.

To all whom it may concern:

Be it known that I, ALOIS J. KAMPE, a citizen of the United States, residing at Chicago, county of Cook, and State of Illinois, have invented certain new and useful Improvements in Draft Apparatus for Stoves, of which the following is a specification.

My invention relates to draft apparatus for heating stoves and the like, and particularly to that class of draft devices which is adapted to be secured to the inside of the pipes of a stove.

The object of my invention is to provide a draft apparatus as mentioned, which may be effectually operated with ease.

A further object of my invention is to provide a draft device as mentioned, which may be readily attached to the ordinary stove-pipe, and one which will be strong, durable and simple of construction, hence of low cost to manufacture.

Other objects will appear hereinafter.

With these objects in view, my invention consists generally in a fan wheel fixed to a vertically disposed shaft, said shaft being rotatably mounted in a suitable frame, and in means on said frame for securely attaching the same to the inside of a stove-pipe.

My invention further consists in a beveled gear fixed to a horizontal shaft, said shaft being suitably mounted in brackets on said fan shaft supporting frame, the teeth of said beveled gear being adapted to mesh with the teeth of a beveled pinion fixed to the upper end of said fan wheel shaft.

My invention further consists in means at the outer end of said horizontal shaft for manually rotating said shaft and hence, said fan wheel.

My invention further consists in certain details of construction and arrangements of parts all as will be fully described hereinafter.

My invention will be more readily understood by reference to the accompanying drawings, forming a part of this specification, and in which,

Figure 1 is a side elevation of my draft apparatus attached, the stove-pipe being broken away so as to expose the same, and Fig. 2 is a top plan view thereof.

Referring now to the drawings, 1 indicates a circular metal band, the outside diameter of which, is substantially the same as the inside diameter of the ordinary circular sheet metal pipe 2. Extending through the center

of said circular band 1 and having its ends 3 secured preferably by a rivet 4 to the band 1 as shown in the drawings, is a preferably rectangular frame 5. Vertically disposed and mounted in suitable bearings through substantially the center of the frame 1, is a shaft 6. Suitably fixed to the upper end 7 of the shaft 6 is a beveled pinion 8, the underface 9 of the lower portion 10 of said pinion 8 resting upon the upper face 5' of the frame 5. Suitably fixed to the lower end 11 of the shaft 6 is an ordinary fan-wheel 12, the diameter of said fan wheel being slightly less than the diameter of the stove-pipe 2. Riveted or otherwise secured, to said frame 5 upon the upper surface 5' thereof, are brackets 13 and 13'. Horizontally disposed and mounted in suitable bearings in the brackets 13 and 13' is a shaft 14, the outer end 15 of said shaft projecting outside of the stove-pipe 2 as shown in the drawing. Suitably fixed to the inner end portion 16 of said shaft 14 is a beveled gear 17 which meshes with said beveled pinion 8 on the fan wheel shaft 6. The bracket 13 against which rests the beveled gear 17, is so positioned on the frame 5 as to keep said beveled gear in constant mesh with the beveled pinion 8. Detachably secured, preferably by screws or rivets 18 to the outer end 15 of the shaft 14, is a suitable handle portion 19.

In attaching my device to a stove-pipe, the stove-pipe is apertured as at 20 to receive the end portion 15 of the shaft 14, the handle portion 19 being detached to facilitate so doing. When the device is in position the band 1 is secured preferably by the rivet 21 to the inside of the stove-pipe. The handle 19 is then attached as stated to the shaft 14 and the device is ready for use.

Having described my invention what I claim as new, and desire to secure by Letters Patent, is:

The combination with an ordinary stove-pipe, of a circular metal band secured to the inside thereof, a rectangular frame secured to said circular band and comprising a pair of horizontal transverse bars and a pair of vertical end bars, a vertically disposed shaft mounted centrally in said frame and having bearings in both of said transverse bars, a fan wheel and a beveled pinion fixed to said shaft the former below said frame and the latter above the same, a horizontally disposed shaft, brackets on the upper bar of

said frame and supporting said horizontal shaft, a beveled gear fixed to said horizontal shaft, said beveled gear being adapted to mesh with said beveled pinion and a crank on the outer end of said horizontal shaft, substantially as described.

In testimony whereof I have signed my

name to this specification in the presence of two subscribing witnesses.

ALOIS J. KAMPE.
